UNITED STATES PATENT OFFICE.

HAROLD W. NICHOLS, OF MAPLEWOOD, NEW JERSEY, ASSIGNOR TO WESTERN ELECTRIC COMPANY, INCORPORATED, OF NEW YORK, N. Y., A CORPORATION OF NEW YORK.

RADIO SYSTEM.

Application filed November 24, 1924. Serial No. 751,728.

To all whom it may concern:

Be it known that I, HAROLD W. NICHOLS, a citizen of the United States of America, residing at Maplewood, in the county of 5 Essex and State of New Jersey, have invented certain new and useful Improvements in Radio Systems, of which the following is a full, clear, concise, and exact description.

10 This invention relates to radio systems and more particularly to high power apparatus for transmitting speech over great distances.

15 In one type of radio telephone systems heretofore proposed, which included amplifying devices supplied with rectified alternating current, it has been the practice to employ some form of filtering device for suppressing the ripple component present in 20 the rectified current supplied to the amplifiers. This was done in order to eliminate the distorting effect due to the ripples, whereby the speech currents produced at the receiving station, except for extraneous 25 interference, are substantially faithful replica of the transmitted speech.

30 In relatively low power arrangements, involving voltages of the order of a few thousand volts in which energy of upwards of one kilowatt is supplied to the antenna, the 35 cost of the filters and the power dissipated in them is small, and hence their use does not materially affect the cost of installation and maintenance, nor the efficiency of the system.

35 In high power systems, however, where energy is supplied to the rectifying devices at several thousand volts and energy of the amount of one hundred kilowatts or more 40 is supplied to the transmission circuit, the initial cost of the filters would be great and the power dissipated in them would be large. As a matter of fact in such a system, the filters would represent a relatively large percentage of the cost of installation and maintenance of the transmitting station and 45 would introduce large power losses.

50 In a second system which has been previously proposed, the speech currents are impressed upon the input circuit of the rectifying devices supplying energy to the amplifiers, and the resulting speech modulated rectified current is supplied to the plate cir-

cuit of an oscillator which generates a carrier wave.

55 In this arrangement a ripple component is continuously transmitted resulting in large power losses. Again the high frequency wave is modulated by speech and the ripple component which appears in the output circuit of the oscillator as a tone. Upon detection at the receiving station the ripples mask the reproduced speech.

60 The present invention provides a system including a lower power apparatus for producing a speech modulated carrier wave, the modulation products of which do not contain a component of carrier frequency; impressing the resultant components upon the input circuit of high power amplifying devices supplied with space current having a relatively large ripple component, and transmitting the resultant carrier wave modulated by both speech and the ripple 65 component. In this arrangement, the ripple component is superimposed upon the speech modulated side band component and does not produce a tone effect in the wave supplied to the transmission circuit. At the 70 receiving station the quality of the speech produced is somewhat impaired, but the intelligibility of the message is practically unaffected. Again, since the ripple component is only transmitted during the time when speech modulated waves are radiated there is a material saving in the energy supplied to the antenna as compared with previously 75 known systems.

80 An object of this invention is to improve the efficiency of high power apparatus for transmitting speech modulated carrier waves without affecting the intelligibility of the message reproduced at the receiving station.

85 For a complete understanding of the invention, reference should be made to the following specification read in conjunction with the attached drawing in which Fig. 1 90 illustrates a radio transmitter embodying the invention, and Fig. 2 shows an alternative method of coupling the lower power apparatus to the high power amplifiers.

95 In Fig. 1 there is shown a complete high power system for transmitting a high frequency wave modulated in accordance with speech. In this system, speech currents are 100 supplied by a circuit 1, which in this in-

stance is shown as including a microphone 2 and battery 3 and may, therefore, be a telephone line, to a modulating apparatus 4 which is supplied with a wave of carrier frequency by a source 5.

The modulating apparatus may be of any well known type, but is preferably similar to that disclosed in U. S. Patent 1,343,807, June 15, 1920 to J. R. Carson. In accordance with the disclosure in this patent, the speech currents from circuit 1 and the carrier wave from source 5 are combined to produce a modulated wave in which the component of carrier frequency is suppressed. Modulation products, therefore, consist solely of the side band components.

The side band components supplied by the modulator 4 are impressed upon the filter which is of the general type described in U. S. Patents 1,227,113 and 1,227,114, May 22, 1917 to G. A. Campbell and is designed to pass without appreciable attenuation one side band of the modulated wave, the other side band being thereby suppressed.

The side band selected by the filter is amplified by the device A which may include as many stages of amplification as may be desirable. The amplified wave is transmitted through the coupling circuit C and impressed upon the input electrodes of the power amplifier Ap consisting of a plurality of parallel connected three-electrode space discharge devices 7. While but three discharge devices are illustrated, it is to be understood that the power amplifier may consist of any number of parallel connected devices of this type.

The coupling circuit C comprises a capacity 8 of low impedance for the high frequency wave shunted by resistance 9, in series with a loop circuit including an inductance 10, a branched circuit having an inductance 11 in one branch and a resistance 12 in the other branch, and a condenser 13. The elements 10, 11-12 and 13 are connected in series, to constitute a loop circuit tuned to the frequency of the high frequency wave. The potential drop across the branch circuit 11-12 is impressed upon the input electrodes of the power amplifier.

Heating current for the cathodes of devices 7 is supplied by the source 15 through a transformer 16.

Space current is supplied to the discharge devices 7 by an alternating current source, herein represented by the secondary winding of a six-phase transformer S, through rectifiers 14 which are illustrated as two-electrode space discharge devices. An alternating current source 17 supplies heating current to the cathode of each of the rectifiers 14 through a transformer 18.

The six-phase windings of the transformer S are arranged in two groups hav-

ing their neutral points connected together by an inter-phase reactor 19. An intermediate point of the reactor is connected to the anodes of the devices 7. With this arrangement, and using a 60 cycle source, for example, the rectified current supplied to the anodes of the power amplifier will contain a principal ripple component of the order of 360 cycles which, therefore, lies in that portion of the speech range within which the larger portion of the energy of speech is concentrated. Ripple components which are multiples of the principal ripple component will ordinarily be too small to be taken into account but they will produce results of the same nature as the principal ripple component and hence may be considered to act in the same manner.

The space current path of the devices 7 may be traced from ground at 20 to the anodes of the rectifiers 14, across the discharge paths within them to their cathodes, the different phase windings of the transformer S, reactor 19, anodes of the devices 7 across the spaces within them to their cathodes and ground at 21.

The alternating current output circuit of the power amplifier Ap extends from the anodes of devices 7 through the condenser 22, the circuit comprising the parallel connected condenser 23 and coil 24, tuned to the high frequency wave, cathodes of devices 7 and across the discharge paths within them to their anodes. The coil 24 is inductively associated with the coil 25 included in the antenna circuit.

Fig. 2 illustrates an alternative arrangement for coupling the amplified A to the power amplifier Ap. This coupling unit may be substituted for that shown between the section lines a-a and b-b of Fig. 1. The primary winding of the transformer 26 is included in the alternating current output circuit of the amplifier A. The secondary winding of this transformer is connected in series with condenser 28 and resistance 29. The secondary winding of transformer 26 and condenser 28 cooperate to constitute a circuit tuned to the frequency of the modulated wave supplied by the amplifier A.

The drop of potential across resistance 29 is impressed upon the input electrodes of the amplifier Ap.

This method of impressing the high frequency wave upon the power amplifier serves to reduce the tendency to produce oscillations of undesired frequencies in the amplifier circuits. This is effected by using a resistance 29 of a value such that the amplitude of the wave impressed upon the input electrodes of the amplifier Ap is so limited that the coupling between its input and output circuits is insufficient to maintain the production of undesired oscillations.

A system similar to that described above, used for transatlantic telephone transmission, consisted of twenty parallel connected devices each adapted to supply upwards of 5 ten kilowatts to the antenna. Current produced by rectifying 60 cycle alternating current, was supplied at from 10,000 to 12,000 volts to the parallel connected devices. The discharge devices are operated with a comparatively large negative grid polarization, so that certain portions of the impressed modulated wave cause the devices to operate on the curved portions of the characteristic, and hence they have an incidental distorting effect.

With this system, while the ripple component was of the order of 360 cycles and constituted approximately 15% of the power supplied to the devices 7, intelligible speech 20 of relatively good quality was reproduced at the receiving station. This may be explained by the fact that the high frequency modulated wave was impressed upon the input electrodes of the devices 7 while the ripple 25 component is applied to the output circuit of these devices and consequently the voltage variations due to the ripple do not appear as a tone in the output circuit of the amplifier. The effect of the ripples is to 30 cause the modulated band to shift back and forth in the frequency spectrum by an amount corresponding to the ripple component, whereby the width of the band transmitted is extended. In other words, the 35 ripple appears in the received signal, not as waves of the ripple frequency but as waves of the speech frequency plus and minus the ripple frequency.

At the receiving station, the incoming 40 widened frequency band was selected by means tuned to pass it without appreciable attenuation and was combined with locally generated oscillations of carrier frequency. There was, therefore supplied to the telephone receiver a composite current consisting of variations representing speech having the ripple component superposed thereon. Thus if the signal wave be represented in 45 frequency as "s" and the ripple frequency by "r" there will appear in the received signal components of frequency $s-r$ and $s+r$ as well as s . If the components of frequencies $s-r$ and $s+r$ are not too large the effect upon the intelligibility and naturalness of the speech is quite immaterial.

The alternating current may be supplied to power amplifiers from a source of four or more phases, whereby the principal ripple component will lie within the range 50 where speech energy is largely concentrated, and the intelligibility of the conversation will not be materially affected. However, the application of the invention is not limited to the use of any particular number of 55 phases.

From the preceding description, it will be seen that the present invention provides a system in which expensive ripple filters are dispensed with, and hence their initial cost and the power losses consequent upon their 70 use are eliminated. Again, since the ripple component is produced only during the time speech is transmitted, the power losses entailed by the presence of the ripples is considerably reduced. Also the intelligibility 75 of the speech reproduced at the distant station is substantially unaffected.

As compared with previously known systems, the arrangement described in this application embodies features of considerable 80 importance, especially when applied to high power systems, since their use permits the initial cost of installation and maintenance, and power losses to be considerably reduced while permitting intelligible speech to be 85 transmitted over long distances.

While the invention has been described with reference to a specific embodiment and specific details have been given in order to clearly and completely disclose its nature, it 90 is to be understood that this invention is not limited to the particular use or details herein set forth but only by the scope of the attached claims.

What is claimed is:

1. A radio transmitting system, comprising means for producing a carrier wave modulated in accordance with speech currents while suppressing the component of carrier frequency, and means for raising 100 said wave to high power comprising an amplifier supplied with energy having an appreciable ripple component.

2. A radio transmitting system, comprising means for producing a single side band speech modulated wave, an amplifier for raising said wave to high power, and means for supplying to said amplifier energy having an appreciable ripple component.

3. A radio transmitting system, comprising means for producing a single side band speech modulated carrier wave, a space discharge amplifier for raising said wave to high power, and means for supplying to said space discharge amplifier energy having an appreciable ripple component.

4. A radio transmitting system, comprising means for producing a single side band speech modulated carrier wave, means for raising said wave to high power comprising a power system including space discharge devices, and means for supplying to said devices energy having an appreciable ripple component.

5. A transmitting system having means for producing a single side band of a signal modulated wave, a space discharge amplifier for amplifying said wave, a source of alternating current of a plurality of phases, and rectifying means for said alternating cur-

rent, whereby said amplifier is supplied with direct current.

6. A transmitting system having means for producing a single side band of a signal modulated wave, a space discharge amplifier for amplifying said wave, a source of alternating current of a plurality of phases, and rectifying means for said alternating current, whereby said amplifier is supplied with direct current having ripples of material value superimposed thereon.

7. A radio transmitting system, comprising means for producing a single side band speech modulated carrier wave, means for raising said wave to high power comprising a power system including space discharge devices, and means for supplying space current to said devices comprising an alternating current source of at least four phases and a rectifier.

8. A modulating system comprising means for producing a single side band-speech-modulated carrier wave, a high power amplifier therefor comprising space discharge devices supplied with space current by a plural phase alternating current source and a rectifier in which the ripple component resulting from rectification is supplied to the space paths of said devices.

30 9. A radio transmitting system, comprising means for producing a single side-band-speech-modulated carrier wave, a high power amplifier therefor including space discharge devices, means for impressing the modulated

wave upon the input circuit of said amplifier, and means for supplying space current to said devices from a plural phase alternating current source and a rectifier, whereby the ripple component resulting from rectification is superposed upon said modulated carrier wave.

10. A modulating system having means for producing a single side band of a signal modulated wave, a space discharge amplifier for amplifying said wave, a source of alternating current of a plurality of phases, rectifying means for said alternating current, whereby said amplifier is supplied with direct current, and means for supplying alternating current for heating the filaments of said devices.

11. A modulating system comprising means for producing a single side-band-speech-modulated carrier wave, a high power amplifier therefor comprising space discharge devices supplied with space current by a plural phase alternating current source and a rectifier in which the ripple component resulting from rectification is supplied to the space paths of said devices, and means for supplying alternating current for heating the filaments of said devices.

In witness whereof, I hereunto subscribe my name this 21st day of November A. D., 1924.

HAROLD W. NICHOLS.
